CLAIM

The ornamental design for a FM radio and wireless speaker housing, as shown and described.

DESCRIPTION

FIG. 1 is a top, front and left side perspective view of a FM radio and wireless speaker housing showing my new design; FIG. 2 is a top, front and right side perspective view thereof; FIG. 3 is a top, rear and right side perspective view thereof; and, FIG. 4 is a top, rear and left side perspective view thereof. The broken lines in the drawings illustrate portions of the FM radio and wireless speaker housing which form no part of the claimed design.

1 Claim, 4 Drawing Sheets
